WRAPPER-ATTACHING MACHINE FOR
SHOE MANUFACTUREWalter Schimming, Staten Island, N.Y., assignor to
Herman Schwabe, Inc., Brooklyn, N.Y., a corporation
of New YorkFiled Apr. 18, 1962, Ser. No. 188,378
16 Claims. (Cl. 12—1)

This invention relates to the manufacture of shoes, especially floater-type shoes, and more particularly to a wrapper-attaching machine for use in the manufacture of such shoes.

The present machine facilitates the manufacture of a casual shoe having a peripheral wrapper, sometimes called a "floater" type shoe. Such a shoe has an upper made of leather or fabric; a sole which is usually thick rubber, say one-half inch thick; and it additionally has a wider strip of rubber secured around the periphery and concealing the edges of the sole and the bottom edge of the upper. The top edge of the strip is sewn to the upper, and the remainder is glued in position. Such a strip is commonly called a wrapper.

This floater shoe differs importantly from a so-called sneaker or athletic shoe in that the latter is vulcanized at high temperature. The floater shoe is not subjected to high temperature, and there is no vulcanization. The wrapper is simply cemented in position.

The sole is applied to the shoe before the wrapper is cemented in position. One object of the present invention is to provide means to apply a substantial inward radial pressure against the wrapper to obtain a strong cemented bond. With this object in view I provide a plurality of horizontal hydraulic cylinders which exert the desired inward radial pressure. This pressure tends to deform the rubber sole, thereby reducing the radial pressure, and spoiling the intended relation of the parts of the shoe during the cementing operation. Equally or even more important, the deformation of the sole may spoil the previously established bond between the top surface of the sole and the bottom of the insole. Deformation of the shoe also may tear the wrapper at its sewed seam.

Accordingly, one primary object of the present invention is to eliminate deformation of the sole and shoe while subjecting them to substantial inward radial pressure in order to firmly bond the wrapper.

A further object of the present invention is to apply the same to a machine somewhat like the sole laying machine disclosed in Haas Patent 2,783,486 granted March 5, 1957, and entitled "Shoe Sole Attaching Machine." Such a machine provides two stations, so that the operator may cement and load one shoe into the machine while the preceding shoe is setting under pressure. The application of pressure to the next shoe may be automatically accompanied by the release of the preceding shoe, the operator then being free to remove the treated shoe and to prepare and load another shoe in the machine. The present invention is also applicable to the machine of Haas Patent 2,843,864 granted July 22, 1958, and entitled "Shoe Sole Attaching Machine," in which the release is timed by adjustable clock control, that is, the two stations are relatively independent of one another.

The mechanism of the aforesaid patents affords a fast rise of a shoe pad carrying a lasted shoe until it reaches the toe and heel stop posts. In accordance with another feature and object of the present invention the radial pressure is delayed until after the shoe is clamped in position.

To accomplish the foregoing general objects, and other

2

more specific objects which will hereinafter appear, my invention resides in the wrapper-attaching machine elements and their relation one to another as are hereinafter more particularly described in the following specification.

5 The specification is accompanied by drawings in which:

FIG. 1 is a perspective view showing a machine embodying features of my invention;

10 FIG. 2 is a plan view, drawn to larger scale, showing one of the shoe pads with four horizontal cylinders for exerting radial pressure on the wrapper of a lasted shoe, the top plate of the shoe pad being removed to better show the movable parts;

15 FIG. 3 is a vertical section taken approximately on the plane of the line 3—3 of FIG. 2, with the top plate restored;

FIG. 4 is a fragmentary vertical section through a lasted shoe with its stitched wrapper, before cementing the same;

20 FIG. 5 is a flow diagram for the machine shown in FIG. 1; and

FIG. 6 is a flow diagram for a different machine embodying the present improvement.

Referring to the drawing, and more particularly to FIG. 4, the shoe comprises an upper 12 which is sewed at its lower edge to an insole 14. The same stitching, or more usually another line of stitching, is employed to stitch a wrapper 16 to the upper 12. Ordinarily one line of stitching will go through two of the parts, while the second line of stitching will go through all three. The wrapper 16 at this time is a band or strip lying above the stitching, as shown in broken lines at 16', but it later is turned down, as shown in solid lines at 16, so that it will lie around the periphery of the outsole 18. A filter, for example cork, is disposed between the insole 14 and the outsole 18, as shown at 20. The soles and filler are preliminarily secured together, as by cementing, or in any other suitable fashion. The construction of the shoe may vary, and is not important in the present invention, so long as there is a peripheral wrapper.

25 The manufacturing step here involved is the cementing of the wrapper 16 to the periphery of the sole 18. For this purpose the wrapper is coated with a cement while it is in the raised position 16'. The periphery of the sole is also coated with cement, and the wrapper is then turned down about the sole and is pressed to adhere the parts together. During this operation the shoe preferably is filled by a last 22. Eventually any excess width of wrapper is trimmed flush with the bottom of the sole.

30 Machines have already been proposed to facilitate this cementing operation by applying force against the wrapper to improve the cemented bond. However, these machines have not proved wholly satisfactory. I have found that the pressure heretofore exerted was quite limited compared to optimum pressure for producing a strong bond. I have found further that it will not do to simply increase the pressure, because this leads to deformation of the sole portion of the shoe.

35 Referring now to FIG. 1, the side pressure here is exerted while the lasted shoe is in a press generally resembling a sole laying machine, thereby exerting a substantial vertical pressure on the sole of the shoe to prevent deformation of the same. The machine comprises a frame 24, 26 and 28 carrying a pad box generally designated 30, and a main upright cylinder and piston, in this case located beneath the pad box, for compressing the bottom of a lasted shoe.

40 Referring now to FIG. 3, the pad box has a bottom 32, and two side walls 34. FIG. 2 shows the two end walls 36. There are horizontal cylinders 38 mounted on the outside of the side walls 34, and horizontal cylinders 40 mounted on the outside of the end walls 36.

45 End pieces 42 within the end walls 36 are adapted to

be moved inward by the end cylinders 40. There are also side pieces 44 which are inside the side walls 34 and adapted to be moved inwardly by the side cylinders 38. The side pieces 44 are preferably considerably shorter than the space between the end pieces, in order to provide clearance for inward movement of the end pieces and of the side pieces.

There are yieldable pads 46 and 48 inside the side pieces 44, and yieldable pads 50 and 52 inside the end pieces 42. These are shaped to conform to the shape of the shoe which is to be wrapped. Additional yieldable rubber fillers 54 may be shaped and dimensioned for insertion between the end pieces 52 and the shoe, to adjust the box for a smaller size of shoe.

The cylinders 38 and 40 are preferably single-acting cylinders, and to restore the same to outward or open position they are provided with restoring springs. These may be internal or external. In the present case the end cylinders 40 have internal springs. A compression spring 56 is disposed around piston rod 58 between piston 60 and the end 62 of the cylinder.

The cylinders 38 have no internal restoring springs. Instead each side piece 44 has two outwardly projecting threaded rods 64, and there are compression springs 66 disposed between the side wall 34 of the pad box and an adjustable nut 68. If this nut is turned inward on its threaded rod 64, the force of spring 66 is increased. The adjustment may be locked by use of a lock nut, as shown. If no adjustment is wanted the rods 64 may be smooth rods.

Referring to FIG. 3, a thick yieldable pad 70 is disposed on the bottom 32 of the pad box. The inwardly movable pieces 44 are located just above the pad 70. These pieces preferably have an L cross section, and may be made of short lengths of angle iron. This helps support the pads 46 which are moved inward thereby. Similar remark applies to the end pieces 42. A cover plate 72 is preferably screwed in position over the top of the pad box. The opening through the cover plate is large enough to receive a shoe of large size. The cover plate has been removed in FIG. 2 in order to better show the subjacent parts. If desired, several cover plates may be provided, with openings of different size, to take care of extreme variation in shoe size. The cover plate helps restrain and guide the side pads when in use.

Reverting now to FIG. 1 of the drawing, the machine in preferred form has two stations. The base 24 of the machine acts also as a fluid reservoir and includes a submerged electrically driven pump to supply pressure fluid. There is preferably a spring pressed accumulator to speed the initial movement of the upright cylinders, as is described later. The operation of the stations is controlled by foot treadles 74 and 76, so arranged that one station is released when the other is clamped. The treadles may be a pivoted lever.

In the form here shown the frame of the machine includes a single post 26 extending upward from the base, and a crosshead 28 secured rigidly across the upper end of the post 26. The ends of the crosshead carry horizontal bars 78, and these have depending adjustable toe posts 80, and heel posts 82, which are disposed over the shoe pads 30 for bearing against and arresting upward movement of a lasted shoe in the shoe pad.

In FIG. 1 it will be seen that there are flexible pipes 84 which connect the four horizontal cylinders together, and thence to a regulating valve 86. This leads downward to the upright cylinder or/and to the source of pressure fluid, but because the flow to the horizontal cylinders is intentionally constricted relative to the flow to the upright cylinder, a shoe in the machine is put under vertical pressure before horizontal pressure is applied. This is important and highly preferred because it prevents even momentary deformation of the sole, such as would occur if the horizontal force were to be applied preceding the vertical force.

The delay in the operation of the horizontal cylinders may be obtained by separate valving combined with a special delay means. However, a simpler way to obtain delay is by using a relative constriction of the flow to the horizontal cylinders. This may be adjusted at needle valves 86, one for each station. In FIG. 1 both are shown at the right, but in practice the valve for the left station is at the left, the machine being symmetrical.

The present improvement may be applied to a press which is not clock operated, such as the press in the above mentioned Haas Patent 2,783,486, or to a press which is clock operated, as in the above mentioned Haas Patent 2,843,864. The essential difference is that in the first press one station is released when the other is clamped, and vice-versa, whereas in the second press each station is clamped independently by touching a separate treadle, and the release depends on the timing set in advance on a clock.

The press illustrated in FIG. 1 is of the first type, and 20 its control mechanism is schematically shown in FIG. 5. The pump 102 supplies fluid under pressure to a valve 104, which is of the sliding piston type. The valve is moved by a valve rod 106 under control of the tiltable treadle previously mentioned. When moved to the left, pressure 25 fluid is supplied to the left hand cylinder 90, while the right hand cylinder 90 discharges through pipe 108 to the reservoir or tank 110. At the same time pressure fluid flows through pipe 88, adjustable needle valve 86, and the four hoses 84, to the four horizontal cylinders, 30 not shown. When the valve is moved to the right hand position, the right hand station is activated, and the left hand station is released. In midposition the supply from the pump preferably but not necessarily is blocked, thus keeping the spring-pressed accumulator 112 under pressure while both stations are released.

Excess fluid returns to the tank from a relief valve 114 which determines the maximum pressure permitted in the system. The accumulator also is loaded during the clamping of either station because after the pistons have moved 40 the accumulator builds up its reserve, and the cylinder pressure builds up. When the valve is shifted to apply pressure to the other station, the accumulator piston is immediately moved by its spring, and helps move the vertical cylinder piston rapidly to clamping position. 45 Thereafter, as the pump continues operating, the accumulator is restored to loaded condition and the pressure in the cylinder builds up.

The pressure gage at the top of FIG. 1 shows the pressure, and helps properly adjust the relief valve (114 in 50 FIG. 5).

The operation of the clock-timed machine may be explained with reference to the flow diagram shown in FIG. 6. This corresponds generally to the flow diagram in FIG. 5 of the aforesaid Patent 2,843,864. One main 55 change is in the addition of the horizontal cylinders 38 and 40 with their flexible hoses 84 leading to regulating valves 86 and pipes 88. These are connected to the lower ends of the main cylinders 90, so that the horizontal cylinders are actuated with the vertical cylinders, except for the 60 effect of the intentionally constricted flow to the horizontal cylinders.

A pump is shown at 160, immersed in a tank of fluid as indicated at 162, and driven by an electric motor 174. The inlet is taken through a sieve 164, and is delivered to a spring accumulator 166, which also may be immersed in the fluid. The pump output is connected through pipe 168 to a pressure relief valve 170, having a control handle 144 located for ready adjustment. Overflow from the 65 relief valve is returned through pipe 172.

The pressure fluid is connected through pipe 176 to a first valve 178 for cylinder 180 at one station, and to cylinder 182 for the other station through a pipe 184 and valve 186. These valves are preferably solenoid actuated, 70 as is indicated by the solenoids 188 and 190. In one posi-

tion of the valve 178 the pressure fluid is connected through pipe 192 and check valve 194 to cylinder 180. In the opposite position of the valve 178 the cylinder 180 is relieved through pipe 196, valve 178, and drain pipe 198, and it should be noted that this circuit bypasses the check valve 194. The valve and pipe arrangement for the cylinder 182 is like that for cylinder 180.

The check valve 194 prevents any lessening of pressure in clamp cylinder 180 when pressure is first applied to clamp cylinder 182, and conversely the check valve 195 of clamp cylinder 182 prevents lessening of pressure in the latter when clamp cylinder 180 is first actuated.

Because of the check valves it is not possible to drain the cylinders through the "B" ports, and it is for this reason that separate "A" ports are provided, with connections which bypass the check valves.

The treadles 244 and 246 are connected to their respective timing clocks 250 and 252, and the latter are connected to the solenoids 188 and 190 of the solenoid valve 178 and 186. When the valves are closed the spring accumulator 166 is charged. When a valve is opened there is a rapid supply of fluid at low pressure from the accumulator. This is adequate to quickly move the pads and shoe to desired position. The pressure then restores the accumulator and builds up to the maximum or "squeeze" pressure.

The pipe connection to the vertical cylinder is short and direct. The pipe connections to the horizontal cylinders are longer and more constricted. Also four hoses lead from a single pipe. The response of the horizontal cylinders is therefore slower than that of the vertical cylinders, which is as it should be, so that the sole is clamped and held before horizontal pressure is applied. This result is further assured by the use of the needle valve 86, which is adjusted to constrict and delay the flow as much as may be necessary.

As a specific example, the upright cylinders may be given a diameter of three inches; the horizontal side cylinders a diameter of one and one-half inches; and the horizontal end cylinders a diameter of one inch. A typical working pressure for the hydraulic system is three hundred fifty pounds per square inch. The rubber pad 70 beneath the shoe may have a hardness of sixty durometers and a thickness of one and one-half inches. The side pads have a height of, say one inch. As will be seen in FIGS. 2 and 3, the side pads are built up of two types of rubber. The outer pads, that is the side pads 46 and the end pads 50, may have a hardness of say seventy durometers, while the inner pads, that is, the side pads 48 and the end pads 52 (and filler pads 54, when used) may have a hardness of say fifty durometers, and are preferably made of good natural gum rubber. The filler pads 54 have gradually tapering sides which overlap the side pads 48, and which provide a desired continuity around the periphery of the shoe.

It will be understood that the foregoing dimensions and values are given solely by way of example, and are not intended to be in limitation of the invention.

It is believed that the construction and operation of my improved wrapper-attaching machine, as well as the advantages thereof, will be apparent from the foregoing detailed description. It will also be apparent that while I have shown and described my invention in several preferred forms, changes may be made in the structures shown, without departing from the scope of the invention as sought to be defined in the following claims.

In the claims the reference to the use of rubber pads is not intended to exclude other resiliently yieldable materials having the properties of rubber. The reference to hydraulic cylinders is not intended to exclude the use of air instead of oil or water as a fluid medium. The reference in the claims to the horizontal cylinders being on the outside of the side walls or end walls is

not intended to exclude a cylinder mounting a part of which happens to pass partly or wholly through the wall.

I claim:

- 5 1. A wrapper-attaching machine comprising a frame carrying a pad box and a main upright cylinder and piston for compressing the bottom of a lasted shoe, said pad box having a bottom, two side walls, and two end walls, horizontal cylinders on the outside of the end walls, horizontal cylinders on the outside of the side walls, end pieces within the end walls to be moved inward by the end cylinders, side pieces within the side walls to be moved inward by said side cylinders, yieldable pads inside said end and side pieces shaped to conform to the shape of the shoe which is to be wrapped, and pipes connecting the four cylinders together for simultaneous operation and thence to the upright cylinder.
- 10 2. A wrapper-attaching machine as defined in claim 1, in which the base of the machine acts as a fluid reservoir, and in which the upright cylinder is beneath the pad box, and in which the frame has adjustable toe and heel posts disposed over the shoe pad for bearing against and arresting upward movement of a lasted shoe in said shoe pad.
- 15 3. A wrapper attaching machine as defined in claim 1 in which the bottom of the pad box is covered by a bottom pad, and in which the end pieces and side pieces and the pads moved thereby are disposed over the bottom pad, whereby the entire area of the shoe bottom is under vertical supporting pressure to prevent deformation of the shoe bottom by the inward force exerted by the end and side pieces.
- 20 4. A wrapper-attaching machine comprising a frame carrying a pad box and a main upright cylinder and piston for compressing the bottom of a lasted shoe, said pad box having a bottom, two side walls, and two end walls, horizontal cylinders on the outside of the end walls, horizontal cylinders on the outside of the side walls, end pieces within the end walls to be moved inward by the end cylinders, side pieces within the side walls to be moved inward by said side cylinders, yieldable pads inside said end and side pieces shaped to conform to the shape of the shoe which is to be wrapped, and pipes connecting the four cylinders together for simultaneous operation and thence to the upright cylinder, the flow to the horizontal cylinders being delayed relative to the flow to the upright cylinder so that in operation a shoe is put under vertical pressure before horizontal pressure is applied.
- 25 5. A wrapper-attaching machine in which there are two stations as defined in claim 4, and in which there is a fluid supply circuit to the upright cylinders, and in which the fluid circuit includes a spring-pressed accumulator to speed the initial movement of the upright cylinders, and in which the upright cylinders are beneath the pad boxes, and in which the operation of the stations is started by foot treadles, and in which there are adjustable toe and heel posts disposed over the shoe pads for bearing against and arresting upward movement of a lasted shoe in said shoe pad.
- 30 6. A wrapper attaching machine as defined in claim 4 in which the bottom of the pad box is covered by a bottom pad, and in which the end pieces and side pieces and the pads moved thereby are disposed over the bottom pad, whereby the entire area of the shoe bottom is under vertical supporting pressure to prevent deformation of the shoe bottom by the inward force exerted by the end and side pieces.
- 35 7. A wrapper-attaching machine comprising a frame carrying a pad box and a main upright hydraulic cylinder and piston for compressing the bottom of a lasted shoe, said pad box having a bottom and two side walls and two end walls, horizontal hydraulic cylinders on the outside of the end walls, horizontal hydraulic cylinders on the outside of the side walls, end pieces within
- 40
- 45
- 50
- 55
- 60
- 65
- 70
- 75

the end walls to be moved inward by the end cylinders, side pieces within the side walls to be moved inward by said side cylinders, said side pieces being shorter than the space between the end pieces to provide clearance affording simultaneous inward movement of the end pieces and side pieces, yieldable pads inside said end and side pieces shaped to conform to the shape of the shoe which is to be wrapped, and pipes connecting the four cylinders together for simultaneous operation and thence to the upright cylinder, the flow to the horizontal cylinders being constricted relative to the flow to the upright cylinder so that in operation a shoe is put under vertical pressure before horizontal pressure is applied.

8. A wrapper-attaching machine as defined in claim 7, in which the base of the machine acts as a fluid reservoir and includes a submerged electrically driven pump to supply pressure fluid, and in which the upright cylinder is beneath the pad box, and in which the frame has adjustable toe and heel posts disposed over the shoe pad for bearing against and arresting upward movement of a lasted shoe in said shoe pad.

9. A wrapper attaching machine as defined in claim 7 in which the bottom of the pad box is covered by a bottom pad, and in which the end pieces and side pieces and the pads moved thereby are disposed over the bottom pad, whereby the entire area of the shoe bottom is under vertical supporting pressure to prevent deformation of the shoe bottom by the inward force exerted by the end and side pieces.

10. A wrapper-attaching machine comprising a frame carrying a pad box and a main upright hydraulic cylinder and piston for compressing the bottom of a lasted shoe, said pad box having a bottom and two side walls and two end walls, in rectangular relation, horizontal hydraulic cylinders on the outside of the end walls, horizontal hydraulic cylinders on the outside of the side walls, end pieces within the end walls to be moved inward by the end cylinders, side pieces within the side walls to be moved inward by said side cylinders, said side pieces being shorter than the space between the end pieces to provide clearance affording simultaneous inward movement of the end pieces and side pieces, all of said horizontal cylinders being single acting, restoring springs for moving the end and side pieces outward, yieldable pads inside said end and side pieces shaped to conform to the shape of the shoe which is to be wrapped, and pipes connecting the four cylinders together for simultaneous operation and thence to a regulating valve and thence to the upright cylinder, the flow to the horizontal cylinders being constricted relative to the flow to the upright cylinder so that in operation a shoe is put under vertical pressure before horizontal pressure is applied.

11. A wrapper-attaching machine in which there are two stations as defined in claim 10, and in which there is a fluid supply circuit to the upright cylinders, and in which the fluid circuit includes a spring-pressed accumulator to speed the initial movement of the upright cylinders, and in which the upright cylinders are beneath the pad boxes, and in which the operation of the stations is started by foot treadles, and in which there are adjustable toe and heel posts disposed over the shoe pads for bearing against and arresting upward movement of a lasted shoe in said shoe pad.

12. A wrapper attaching machine as defined in claim 10 in which the bottom of the pad box is covered by a bottom pad, and in which the end pieces and side pieces and the pads moved thereby are disposed over the bottom pad, whereby the entire area of the shoe bottom is under vertical supporting pressure to prevent deformation of the shoe bottom by the inward force exerted by the end and side pieces.

13. A wrapper-attaching machine comprising a frame

5 carrying a pad box and a main upright hydraulic cylinder and piston for compressing the bottom of a lasted shoe, said pad box having a bottom, two side walls, and two end walls, a thick yieldable pad resting on the bottom, horizontal hydraulic cylinders on the outside of the end walls, horizontal hydraulic cylinders on the outside of the side walls, end pieces within the end walls to be moved inward by the end cylinders, side pieces within the side walls to be moved inward by said side cylinders, all of said horizontal cylinders being single acting cylinders, restoring springs for moving the end and side pieces outward, yieldable pads inside said end and side pieces shaped to conform to the shape of the shoe which is to be wrapped, pipes connecting the four cylinders together for simultaneous operation and thence to the upright cylinder, and adjustable means to constrict the flow to the horizontal cylinders relative to the flow to the upright cylinder so that in operation a shoe is put under vertical pressure before horizontal pressure is applied.

15 14. A wrapper attaching machine as defined in claim 13 in which the end pieces and side pieces and the pads and fillers moved thereby are disposed over the aforesaid thick bottom pad, whereby the entire area of the shoe bottom is under vertical supporting pressure to prevent deformation of the shoe bottom by the inward force exerted by the end and side pieces.

20 15. A wrapper-attaching machine comprising a frame carrying a pad box and a main upright hydraulic cylinder and piston for compressing the bottom of a lasted shoe, said pad box having a bottom, two side walls, and two end walls, a thick yieldable rubber pad resting on the bottom, horizontal hydraulic cylinders on the outside of the end walls, horizontal hydraulic cylinders on the outside of the side walls, end pieces within the end walls to be moved inward by the end cylinders, side pieces within the side walls to be moved inward by said side cylinders, said side pieces being shorter than the space between the end pieces to provide clearance affording simultaneous inward movement of the end pieces and side pieces, all of said horizontal cylinders being single acting cylinders, restoring springs for moving the end and side pieces outward, yieldable rubber pads inside said end and side pieces shaped to conform to the shape of the shoe which is to be wrapped, additional yieldable rubber fillers shaped and dimensioned for insertion between the end pieces and the shoe to adjust for a smaller size of shoe, a source of pressure fluid, and flexible pipes connecting the four cylinders together for simultaneous operation and thence to a regulating valve and thence to the upright cylinder and the source of pressure fluid, the flow to the horizontal cylinders being delayed relative to the flow to the upright cylinder so that in operation a shoe is put under vertical pressure before horizontal pressure is applied.

25 16. A wrapper attaching machine as defined in claim 15 in which the end pieces and side pieces and the pads and fillers moved thereby are disposed over the aforesaid thick bottom pad, whereby the entire area of the shoe bottom is under vertical supporting pressure to prevent deformation of the shoe bottom by the inward force exerted by the end and side pieces, and in which there is a top plate disposed over and concealing the end and side pieces, said top plate having an opening large enough to freely receive a shoe being treated.
